UNITED STATES PATENT OFFICE.

FRANCIS B. COCKBURN, OF RIDGWAY, PENNSYLVANIA.

REVERSING MECHANISM FOR MACHINE-TOOLS.

No. 800,428.

Specification of Letters Patent.

Patented Sept. 26, 1905.

Application filed January 3, 1905, Serial No. 239,365.

To all whom it may concern:

Be it known that I, FRANCIS B. COCKBURN, a subject of the King of England, residing at Ridgway, in the county of Elk and State of Pennsylvania, have invented Improvements in Reversing Mechanism for Machine-Tools, of which the following is a specification.

My invention relates to mechanism for reversing machine-tools and the like; and the object thereof is the provision of a device of this character applicable to reciprocating machine-tools and other machines requiring reversal, wherein the necessity of shifting a belt, with its accompanying disadvantages, is overcome.

In carrying out my invention I employ a bracket, a frame pivotally mounted therein, shafts journaled in said frame, a pulley on each of said shafts, means for turning said shafts in opposite directions, a drive-shaft for the machine to be operated, a pulley on the drive-shaft, belts passing around the last-foresaid pulley and respectively around the pulleys mounted in said frame, means for rocking said frame in one direction or the other to tighten one or the other of said belts, means for automatically operating the aforesaid means, means for returning and maintaining said frame in a normal central position, and means for limiting the rocking movement of said frame, all of which will be hereinafter more particularly described.

In the drawings, Figure 1 is an end elevation illustrating my improved reversing mechanism as embodied in a planer. Fig. 2 is a front elevation of the same. Fig. 3 is a plan of the same, and Fig. 4 is a diagrammatic view illustrating a modification of the means for driving the mechanism.

a represents the bed of the machine to be operated, which I have conveniently illustrated as the bed of a planer.

b represents a standard secured in the bed **a**, and **c** a bracket which is supported by the standard **b**. The bracket **c** is provided with uprights 2, in which a rocking frame **d** is pivotally mounted upon suitable short shafts **d'**, secured in the upper ends of the uprights 2. Shafts **e f** are journaled in the frame **d**, and

on one end of the shaft **e** a gear 3 is secured and on the corresponding end of the shaft **f** a gear 4 is secured, said gears 3 and 4 meshing with one another and are, moreover, adapted to be changeable for the purpose of varying the relative speeds of pulleys **g** and **h**. On the opposite end of the shaft **e** is a gear 5,

meshing with the gear 6, secured on a shaft 7, one end of which is preferably journaled in the same bearing as the inner shaft **d'**, and this shaft 7 (which may be termed an "intermediate" shaft) is connected to the power-shaft directly or by means of a belt and pulley, as may be found expedient. Gears 3 and 4 are omitted from Fig. 2 in order to more clearly illustrate the other parts.

g represents a pulley which is mounted on the shaft **e**, and **h** a similar pulley, which is mounted on the shaft **f**.

8 is a drive-shaft for the planer, and **9** a suitable yoke secured to the base **a** and in which at one end the shaft **8** is journaled.

i represents a pulley mounted on the shaft **8**, and **k l** are belts which pass around the pulley **i** and respectively around the pulleys **g** and **h**.

m represents a cylinder, which is conveniently mounted on the bracket **c** and is provided with a piston 10 and piston-rod 11, which latter is connected to one side of the rocker-frame **d** by means of the link 12, and the piston 10 may be operated pneumatically or hydraulically to rock said frame in one direction or the other to tighten either the belt **l** or the belt **k**, and this piston may be operated manually or automatically by the operation of the machine. In the present case this automatic operation may be effected through the arm 13, connected to the valve-stem of the cylinder **m**, a link 14 connecting the arm 13 with an arm 15, which latter is connected to a rod 16, journaled in suitable bearings secured to the side of the standard **b**, an arm 17, connected to the rod 16, and a rod 18, connecting the arm 17 with an arm 19, which latter is secured to a dog **n**, pivotally connected to the base of the machine at 20 and provided with lugs 21 22, the lug 21 being so placed as to contact with an adjustable block 23 and the lug 22 with an adjustable block 24, which blocks may be caused to travel with the frame of the machine and by which it is believed it will be apparent that the action of the piston in the cylinder **m** may be controlled.

o represents an arm which is preferably secured to the frame **d** in a depending position, and at the lower end of the arm **o** there is a gear-segment 25, which meshes with a pinion 26, mounted on a suitable shaft 27, fixed in the bracket **c**. An arm 28 is fixed to the pinion 26, and at the end of the arm 28 is a weight 29, by means of which, acting through

105
110

this shaft and pinion and the rack, the frame *d* is normally maintained in a central position, with the shafts *e* and *f* horizontally disposed. In order to limit the rocking movement of the 5 pivoted frame *d*, I prefer to employ stops 30 and 31, which stops may conveniently comprise lugs on opposite sides of one or both of the uprights 2 of the bracket *c*, and which lugs are provided with suitable screws, whose position may be varied at will to limit the 10 rocking movement of the said pivoted frame.

In the initial or normal condition of inaction, as shown in the drawings, the frame *d* is so maintained by means of the weight 29, rack 25, and pinion 26 that the shafts *e* and *f* are substantially horizontal, and when the intermediate shaft 7 is turned the shaft *e* will be turned in one direction through the gears 5 and 6 and that the shaft *f* will be turned in the opposite direction through the gears 3 and 4, and in this position neither of the belts is sufficiently taut to drive the machine. If now the valve-stem of the cylinder is turned, which in the first instance may be done manually or at all times, if so desired, the piston will be actuated to rock the frame *d* in one direction or the other to tighten one or the other of said belts to drive the machine in the desired direction; depending of course upon the direction in which the piston was moved and the direction of rotation of the intermediate shaft 7. After starting the machine the reversals may, as illustrated, be made automatically by the automatic control of the valve-stem through the arms, rods, dogs, and stops, as hereinbefore described; or manually. It will also be apparent with reference to Fig. 4 that should it be inconvenient to drive the mechanism by an intermediate shaft which is in alinement with the shafts upon which the frame *b* is pivotally mounted the drive may be effected from the shaft 32 and suitable pulley and belt, the shaft 32 being placed in the same horizontal plane with the shafts *e* and *f* and the pivotal shafts *d*' when these latter shafts are in their central or horizontal position; thus dispensing with the gears 5 and 6 and the shafts 7.

I claim as my invention—

50 1. In a reversing mechanism for machine-tools and the like, and in combination; a support, a frame pivotally mounted therein; shafts journaled in said frame; a pulley mounted on each of said shafts, means for
55 turning said shafts in opposite directions, a drive-shaft for the machine to be operated; pulleys thereon, belts passing around the last-foresaid pulleys and respectively around the pulleys mounted in said frame; means for
60 rocking said frame in one direction or the other to tighten one or the other of said belts, and means for automatically returning and normally maintaining said frame in a horizontal position when inoperative.

65 2. In a reversing mechanism for machine-

tools and the like, and in combination, a support, a frame pivotally mounted therein, shafts journaled in said frame, a pulley mounted on each of said shafts, means for turning said shafts in opposite directions, a 70 drive-shaft for the machine to be operated, a pulley thereon, belts passing around the last aforesaid pulley and respectively around the pulleys mounted in said frame, means for rocking said frame in one direction or the 75 other to tighten one or the other of said belts, means for automatically operating the last-aforesaid means, and means for automatically returning and maintaining said frame normally in a horizontal position 80 when inoperative.

3. In a reversing mechanism for machine-tools and the like, and in combination, a support, a frame pivotally mounted therein, shafts journaled in said frame, a pulley 85 mounted on each of said shafts, means for turning said shafts in opposite directions, a drive-shaft for the machine to be operated, a pulley thereon, belts passing around the last-foresaid pulley, and respectively around 90 the pulleys mounted in said frame, means for rocking said frame in one direction or the other to tighten one or the other of said belts, means for automatically returning and maintaining said frame normally in position 95 when inoperative, and means for limiting the rocking movement of said frame.

4. In a reversing mechanism for machine-tools and the like, and in combination, a support, a frame pivotally mounted therein, shafts journaled in said frame, a pulley mounted on each of said shafts, means for turning said shafts in opposite directions, a drive-shaft for the machine to be operated, a pulley thereon, belts passing around the last-foresaid pulley and respectively around the pulleys mounted in said frame, means for rocking said frame in one direction or the other to tighten one or the other of said belts, means for automatically operating the last-foresaid means, means for automatically returning and maintaining the said frame normally in a horizontal position when inoperative, and means for limiting the rocking movement of said frame.

5. In a reversing mechanism for machine-tools and the like and in combination, a support, a frame pivotally mounted therein, shafts journaled in said frame, a pulley mounted on each of said shafts, a gear on 120 the end of one of said shafts, a gear on the corresponding end of the other of said shafts, said gears meshing with one another, means for turning one of said shafts whereby the other of said shafts turns in the opposite direction through said gears, a drive-shaft for the machine to be operated, a pulley thereon, belts passing around the last-foresaid pulley and respectively around the pulleys mounted in said frame, a cylinder, a piston therein, a 125 130

piston-rod therefor, a connection between said piston-rod and the said frame, means for automatically controlling the operation of said piston to determine the direction in which the said frame is to be rocked, a depending arm connected to said frame, a gear-segment integral with the said arm, a pinion meshing with the said rack, a shaft on which said pinion is mounted, an arm secured on said shaft and a weight connected to the last-foresaid arm, whereby the said frame is normally maintained in a horizontal position when inoperative.

6. In a reversing mechanism for machine-tools and the like, and in combination, a support, a frame pivotally mounted therein, shafts journaled in said frame, a pulley mounted on each of said shafts, a gear on the end of one of said shafts, a gear on the corresponding end of the other of said shafts, said gears meshing with one another, means for

turning one of said shafts whereby the other of said shafts turns in the opposite direction through said gears, a drive-shaft for the machine to be operated, a pulley thereon, belts 25 passing around the last-foresaid pulley and respectively around the pulleys mounted in said frame, a cylinder, a piston therein, a piston-rod therefor, a connection between the said piston-rod and the said frame, means for automatically controlling the operation of said piston to determine the direction in which the said frame is to be rocked, and adjustable stops placed on both sides of said support for limiting the rocking movement 30 of said frame.

Signed by me this 8th day of December, 1904.

FRANCIS B. COCKBURN.
